ATTORNEY.

UNITED STATES PATENT OFFICE.

FREDERICK OWEN, OF DETROIT, MICHIGAN.

WASHING-MACHINE.

Specification of Letters Patent. Patented Sept. 27, 1921.

1,391,848.

Application filed February 28, 1921. Serial No. 448,297.

To all whom it may concern:

Be it known that I, FREDERICK OWEN, a citizen of the United States, residing at Detroit, in the county of Wayne and State 5 of Michigan, have invented certain new and useful Improvements in Washing-Machines, of which the following is a specification.

This invention relates to washing machines and has for its object an improved 10 washing machine drum that may be driven continuously in one direction as distinguished from the well known oscillatory machine. The object is to provide a drum which is provided with means for working 15 the clothes first to one end and then to the opposite end in such a manner as not to tangle the same.

In the drawings,

Figure 1 is a side elevation of the drum 20 with the lid removed.

Fig. 2 is a cross section on the line 2—2 of Fig. 1.

Fig. 3 is a detail of one of the blades.

Most machines of the drum type utilize 25 an oscillatory drum which turns first in one direction and then reverses. This requires considerable power to overcome the inertia of the parts in stopping the rotating movement and accelerating the movement in the 30 opposite direction. Furthermore, it requires a complicated reversing gear and results in undue wearing of the parts due to the strains due to stopping the drum and accelerating the drum in the reverse movement. It is 35 the object of the present invention to provide a drum which can be run continuously in one direction and at the same time get the oscillatory movement for the clothes by causing them to travel from end to end of 40 the cylinder. This is accomplished without tangling them.

In the drawing, *a* designates a drum which is provided with an opening *b* which may be closed by any suitable lid.

The idea is simply to employ a pair of 45 blades or paddles, or for that matter, any appropriate number of blades or paddles could be employed. These blades or paddles extend from end to end and are concave 50 on one side and convex on the other. It is only in their broad senses that "concave" and "convex" are applicable to the blade construction shown for the reason that, strictly speaking, these blades are not 55 rounded but happen to be shown in the

drawings as angularly bent in at their centers along the lines *c*. However, a technically concave or convex blade will do the same work, hence I use the words "convex" and "concave" in their broader sense, hollow 60 on one side and having a converse construction on the opposite side. The blades are large at one end and gradually taper so as to be much narrower at the opposite end. The blades, furthermore, are attached along 65 their major length to the inside of the drum on right and left helix segments, for instance, the blade *d* describes a part of a left hand helix from the point *e* to the point *f*, while the blade *h* describes a right hand 70 helix segment from the point *g* to the point *i*, where it is attached to the drum. Furthermore, each blade is twisted about its major axis.

The operation is simple: The drum is rotated continuously in one direction by any suitable source of power. The mass of clothes is caught by the hollow surfaces of one of the blades, for instance, the lower blade in Fig. 2. This carries the clothes up 80 the side of the drum, and by reason of the helical pitch of the blade forces the mass of clothes toward the small end of the blade, which is the end removed from the observer in Fig. 2. At the same time the twisting 85 disposition of the blade serves to turn the clothes and thereby agitate them in the water during the end movement. When the clothes reach the remote end of the cylinder and when the blade that carries them is 90 about to pass the highest point reached in the rotation of the drum, the clothes drop off from the small end of the blade into the large end of the other blade, which is substantially at the low point of the drum at 95 this time.

The same process is repeated when the clothes are forced to the near end of the drum by the blade that now carries them, which is of the opposite pitch. Obviously 100 the clothes are first worked from one end of the cylinder and then dropped from the top of the cylinder to the bottom and then worked to the opposite end of the cylinder and then dropped from top to bottom, in 105 the meantime being turned by the twist in the blades. This operation being continuously repeated, it very successfully agitates the clothes in the water and at the same time the clothes are not tangled for as fast as one 110

blade twists them in one direction the opposite blade reverses the twisting so as to untangle them.

What I claim is:

- 5 1. In a washing machine, a drum arranged for containing clothes and for a cleansing liquid, said drum having blades therein with portions having right and left hand pitches or helical arrangements on the drum, each 55 blade extending substantially from end to end of the cylinder.
- 10 2. In a washing machine, a drum arranged for containing clothes and for a cleansing liquid, said drum provided with blades there- 15 in having their major portions where attached to the interior of the drum describing parts of right and left hand helixes.
- 15 3. In a washing machine, a drum arranged for containing clothes and for a cleansing liquid, said drum having blades, the major 20 portions of which have opposite pitches around the drum, each blade extending sub- stantially from end to end of the cylinder.
- 20 4. In a washing machine, a drum arranged for containing clothes and for a cleansing liquid, said drum provided with blades se- 25 cured to the inside of the drum and having opposite pitches around the inside of the drum and larger at one end than the other.
- 25 5. In a washing machine, a drum arranged for containing clothes and for a cleansing liquid, said drum provided with blades on the inside having opposite pitches from a 30 position of parallelism with the drum axis around the interior of the drum, said blades concave on one side and convex on the other.
- 30 6. In a washing machine, a drum arranged for containing clothes and for a cleansing liquid, said drum having blades secured to 35 the inside arranged on oppositely-directed helixes on the interior of the drum and hollow on one side and convex on the other and smaller at one end than at the other.
- 35 7. In a washing machine, a drum arranged for containing clothes and for a cleansing liquid, said drum having blades secured to 40 the inside of the drum on oppositely-directed helixes, the said blades being convex on one side and concave on the other and smaller at one end than at the other, the small end of 45 one blade being at one end of the drum and the small end of the other blade being at the 50 opposite end of the drum and conversely with the large end of the blades.
- 45 8. In a washing machine, a drum arranged 55 for containing clothes and for a cleansing liquid, said drum having blades secured to the interior of the drum on oppositely-directed helixes and the said blades twisting about their major axes.
- 50 9. In a washing machine, a drum arranged 60 for containing clothes and for a cleansing liquid, said drum having blades secured to the interior of the drum on oppositely-di- rected helixes, the said blades each twisting 65 from one end to the other, the two blades twisting in opposite directions.
- 55 10. In a washing machine, and in a drum thereof, a blade or paddle secured to the interior of the drum on a pitch or helix 70 around the drum.
- 60 11. In a washing machine, a drum ar- 75 ranged for containing clothes and for a cleansing liquid, said drum having a blade secured to the interior thereof on a helix segment and said blade twisting on its major axis.
- 65 12. In a washing machine, a drum ar- 80 ranged for containing clothes and for a cleansing liquid, said drum provided with a blade therein secured to the drum on a helix segment and larger at one end than at the other end and twisting on its major axis.
- 70 13. In a washing machine, a drum ar- 85 ranged for containing clothes and for a cleansing liquid, said drum provided with a blade convex on one side and concave on the other secured to the interior of the drum on a helix segment and larger at one end than at the other end and twisting on its major axis.
- 75 14. In a washing machine, a drum ar- 90 ranged for containing clothes and for a cleansing liquid, said drum rotating on its axis and means for thrusting the clothes first to one end and then to the other of the drum.
- 80 15. In a washing machine, a container for 95 the clothes capable of actuation, and means for thrusting the clothes alternately across such line of actuation.

In testimony whereof I affix my signature.

FREDERICK OWEN.
